COMBINED PULL AND BACKING PLATE FOR DOORS, DRAWERS, AND THE LIKE

Donald Albert Winton, Pasadena, Calif., assignor to
Hyer Hardware Mfg. Co., Anaheim, Calif., a corpora-
tion of California

Filed Apr. 7, 1969, Ser. No. 16,592

Term of patent 14 years

Int. Cl. D8—03

U.S. Cl. D8—138

FIG. 1.

FIG. 2.

FIG. 3.

FIG. 1 is a front elevation of a combined pull and backing plate for doors, drawers, and the like showing my new design;

FIG. 2 is a side elevation thereof; and

FIG. 3 is an end elevation thereof.

I claim:

The ornamental design for a combined pull and back-
ing plate for doors, drawers, and the like, as shown.
